UNITED STATES PATENT OFFICE.

HIRAM COWELL, OF ZANESVILLE, OHIO.

BOILER-FURNACE.

SPECIFICATION forming part of Letters Patent No. 275,805, dated April 17, 1883.

Application filed December 22, 1882. (No model.)

To all whom it may concern:

Be it known that I, HIRAM COWELL, of Zanesville, in the county of Muskingum and State of Ohio, have invented a certain new and Improved Boiler-Furnace; and I do hereby declare the following to be a full, clear, and exact description of the same, reference being had to the accompanying drawings, forming part of this specification, in which—

10 Figure 1 is a side elevation of a furnace constructed in accordance with my invention. Fig. 2 is a longitudinal sectional view of the same.

Similar letters of reference in the several figures denote the same parts.

15 My invention relates particularly to improvements upon the furnace for which a patent was granted me January 20, 1880, numbered 223,635; and it consists in certain novel 20 features of construction which I will first describe and then point out in the claims.

In the accompanying drawings, A represents a steam-boiler; B, the fire-box of the furnace, having the grate O and a low wall, C, at 25 its back. Behind the wall C is a perforated wall, F, arched at its bottom and built up to the boiler, as shown. Between the wall C and wall F is a space, G, to which access may be had through an opening at the end, closed by 30 slide, E, for the purpose of removing soot and cinders from said space when occasion requires. Still farther back under the boiler is a second perforated wall, H, similar to F, except that it is not arched at the bottom. The 35 space N, between the two walls F and H, constitutes a combustion-chamber. Behind the second perforated wall H is a second combustion-chamber, K, containing a low deflecting-wall, J, as shown.

40 Extending across the space N, between the perforated walls F and H, just below the lower line of perforations in said walls, is a grating, G', composed preferably of fire-brick with intervening air-spaces between them, and across 45 the space between the perforated wall H and low wall J is another similar grating, I'.

Fresh external air can be admitted to the 50 spaces G and I, below the gratings G' and I', through suitable openings controlled by valves G² and I², respectively.

In the operation of the furnace the smoke and other volatile products of combustion pass from the fire-box over the low wall C down 55 into the space G, and a portion passes through perforations in the wall F, while another por-

tion passes under the arch of said wall and into the space N under the grating G', where, commingling with the fresh external air admitted to said space N, they pass up through the grating, and, meeting with the portion passed through the perforation of wall F, pass together through the perforations of the wall H. Here they are further commingled with a supply of fresh air admitted in the space I, and, rushing up through the grating I and 65 striking the wall J, are deflected into the combustion-chamber K and pass thence under the boiler and through the flues and out.

The various walls and gratings through which the volatile products pass are very 70 highly heated, and divide and break up said products and whirl them about and thoroughly commingle them with the fresh air supplied at the various points, and effect their most thorough combustion, thus completely utilizing 75 them and greatly increasing the heating capacity of the furnace.

The perforations f h in the walls F and H, respectively, are preferably made tapering from front to rear, so that the smoke, &c., shall enter them freely, but be compressed at the instant of discharge, thereby causing a more rapid commingling with the fresh-air supply; but said perforations may be made with parallel sides or in any other preferred form, if 85 desired.

The low wall C, at the back of the fire-box, performs the important function of preventing the fuel from being banked against the perforated wall F, so as to close the perforations 90 therein, as would be the case with a furnace constructed on the plan of my former patent, were not great care exercised.

Having thus described my invention, I claim as new—

1. In the herein-described furnace, the combination of the low wall C, the arched perforated wall F, the perforated wall H, the air-inlets G² I² behind walls F H, respectively, and the deflecting-wall J, substantially as described.

2. The combination, with the low wall C, the perforated wall F, arched at the bottom, with the second perforated wall, H, deflecting-wall J, and the gratings G I, and the several air-inlets, the whole arranged substantially as described, for the purpose specified.

Witnesses: HIRAM COWELL.
